(57) **CLAIM**

The ornamental design for a bucket retainer, as shown and described.

DESCRIPTION

FIG. 1 is a perspective front view of bucket retainer, showing my new design;

FIG. 2 is a front side view with the back side view being a mirror image thereof;

FIG. 3 is a left side view thereof;

FIG. 4 is a right side view thereof;

FIG. 5 is a top side view thereof; and,

FIG. 6 is a bottom side view thereof.

In the drawings, the broken lines represent unclaimed environmental subject matter and form no part of the claim.
